CLAIM

The ornamental design for a portable media playback device as shown and described.

DESCRIPTION

FIG. 1 is a front elevation view of a portable media playback device.

FIG. 2 is a rear elevation view thereof.

FIG. 3 is first side view thereof.

FIG. 4 is a second side view thereof.

FIG. 5 is a top plan view thereof.

FIG. 6 is a bottom plan view thereof.

FIG. 7 is a perspective view thereof.

FIG. 8 is an enlarged portion of FIG. 7; and,

FIG. 9 is another perspective view thereof.

The dashed broken lines in the figures illustrate the portions of the design that form no part of the claimed design.

The dot-dash broken lines bound enlarged portions and form no part of the claimed design.
